UNITED STATES PATENT OFFICE

2,680,245

STAPLING MACHINE

Herbert W. Marano, Brooklyn, N. Y., assignor to
 Wilson-Jones Company, Chicago, Ill., a corpora-
 tion of Massachusetts

Application July 7, 1949, Serial No. 103,420

3 Claims. (Cl. 1-3)

1

This invention relates to a stapling machine for securing together sheets of paper or similar material, and has particular reference to means for unloading the stapling machine in the event that the staples become jammed therein.

One of the objects of the present invention is to provide means for holding the staple slide that may be quickly and easily released to permit removal of the staple slide so that the machine may be unloaded.

Another object of the invention is to provide a simple, inexpensive latch that will securely hold the staple slide in the stapling machine and will not interfere with the regular operation of the stapling machine.

Other objects of the invention will become apparent upon reading the following description, taken in conjunction with the accompanying drawings, in which:

Figure 1 is a perspective view of a stapling machine embodying the invention;

Figure 2 is a perspective view of the stapling machine with the body portion turned about its hinge to show the latch holding the staple slide in position;

Figure 3 is a fragmentary end elevation showing the rear edge of the latch and staple slide;

Figure 4 is an enlarged fragmentary perspective view of the latch and stapling machine structure immediately adjacent the latch;

Figure 5 is a cross sectional view, taken along the line 5-5 of Figure 4;

Figure 6 is a view similar to Figure 4, showing the latch in open position and the staple slide partially retracted;

Figure 7 is a cross sectional view, taken along the line 7-7 of Figure 3, showing the bottom of the body portion of the stapling machine partly in section and partly in elevation;

Figure 8 is a fragmentary bottom elevational view showing the latch in open position and the staple slide partially retracted;

Figure 9 is a cross sectional view, taken along the line 9-9 of Figure 8.

Figure 10 is an enlarged fragmentary perspective view of the front end of the body portion in inverted position, showing the feed plate in engagement with the staples to advance them forwardly of the staple slide;

Figure 11 is an enlarged fragmentary bottom elevational view showing the feed plate after staples have been inserted into the stapling machine, but before the feed plate has been moved to the rear of the staples;

Figure 12 is a view similar to Figure 11 show-

2

ing, in dotted lines, how the fingers of the feed plate are retracted when the feed plate is pushed past the newly inserted staples, and, in solid lines, the position of the feed plate fingers after the feed plate has been pushed past the newly inserted line of staples.

The stapling machine structure will not be specifically described, except as it pertains to the present invention, because the removable staple slide and the latching mechanism may be applied to almost any conventional stapling machine. Although the invention may be utilized in connection with the construction of many other stapling machines, it will be described specifically in connection with the stapling machine disclosed in my co-pending application filed February 15, 1949, under Serial No. 76,497, now Patent No. 2,667,637.

In the drawings, the reference numeral 2 indicates the body portion of a stapling machine hinged to the base portion 3, as indicated at 4. The underside of the body portion is recessed, as indicated at 5 to receive a staple slide 6. The front end of the recess is closed by the front wall 7 of the body portion. The side walls 8 of the body portion are each provided with a longitudinally extending recess 9. The staple slide is provided with a horizontal flange 10 projecting outwardly from each side, and these flanges fit in the recesses 9. The staple slide 6 is slid into the recess 5 from the rear.

A latch 11 is hinged to the rear end wall 12 of the staple slide in any suitable manner. As shown in Figure 9, an end extension 13 of the latch is passed through an aperture 14 in rear end wall 12 and is curled therearound to pivotally secure the latch to the end wall of the staple slide. The latch has a pair of ears 15 depending at right angles from its opposite edges. Each ear is provided with an undercut recess 16 for a purpose hereinafter described. Each side wall 8 is provided at its bottom with an inwardly extending flange 17 having a vertical recess 18 spaced a short distance from the rear end of the body portion and extending at right angles to the adjacent longitudinally extending recess 9. When the staple slide is positioned in the recess 5 with its front end 19 abutting the rear surface of the front wall 7, and the latch 11 is swung about its hinge to overlie the rear end portion of the staple slide, the ears 15 will fit in recesses 18 and the undercut recess 16 will engage the edge of side wall 8 adjacent each recess 18.

The interengagement of the ears 15 with the edge of flange 17 adjacent recess 18 is snug

enough to hold the staple slide firmly in position. However, if it is desired to remove the staple slide to unload the staples 20, the latch may be easily lifted to disengage the ears from recesses 18, and the staple slide may be slid outwardly without difficulty. When the staple slide is removed, the staples may be easily removed from the machine.

A feed plate 21 is slidably mounted on a rod 22 which is secured within staple slide 6. The rod, which passes through rear end wall 12 and an ear 23 struck out of the staple slide, has a head 24 abutting wall 12 and has its other end held in ear 23 in any suitable manner. The feed plate comprises a pair of fingers 25 pivoted to a plate 26, as indicated at 27. Each finger projects rearwardly of plate 26 a slight distance, as indicated at 28. These projecting ends 29 are engaged by a pressure plate 29 urged against them by a coiled spring 30 which encircles rod 22 and has one end bearing against the wall 12 and its other end against plate 29.

The force of spring 30 against the pressure plate constantly urges the feed plate forwardly relative to the staple slide, and also urges the fingers 25 outwardly about their pivots. The side walls 31 of the staple slide are each provided with an elongated slot 32 through which fingers 25 project when they are forced outwardly by spring 30. In the normal position of the feed plate to the rear of staples 20 the fingers 25 engage the rearmost staple 20 and advance the line of staples towards the driving end of the machine, as shown in Figure 10 and in the solid lines of Figure 12.

When the machine is almost empty the feed plate occupies the position shown in Figure 11, and a new line of staples is slid down on the staple slide while the stapling machine is held vertically with its driving end down. The staples and feed plate 29 then occupy the relative positions shown in Figure 11. While the machine is still held vertically the feed plate 29 is pushed upwardly manually against the action of spring 30. The staples are held on the staple slide by thumb pressure against the rearmost staple of the strip when the feed plate is pushed upwardly against the action of spring 30. The pressure of the staples on the outer edges of the fingers 25 causes the fingers to be retracted to a position as shown in dotted lines in Figure 12 so that the feed plate can be pushed towards the rear end of the machine. When the fingers 25 engage the end of slot 32 they are held in their inwardly compressed position by the side walls 31 of the staple slide, and the staples slide freely downwardly on the staple slide. When the rearmost staple has moved below the front edge of fingers 25 the feed plate is released, and spring 30 urges the feed plate downwardly to thereby advance the staples toward the driving end of the machine. The spring 30 exerts enough force against the plate 29 to force the fingers 25 outwardly into slots 32 as soon as the staples are positioned below the end of the slots and the fingers are in register with the slots.

Although I have described a preferred embodiment of my invention in considerable detail, it

will be understood that the description thereof is intended to be illustrative, rather than restrictive, as many details may be modified or changed without departing from the invention. Accordingly, I do not desire to be restricted to the exact structure described, except as limited by the appended claims.

I claim:

1. In a stapling machine, a body portion, the bottom of said body portion being cut away to provide a recessed area, a pair of side walls terminating in flanges adjacent said recessed area, a staple slide positioned between said flanges, said flanges each being notched in its bottom surface, and a latch secured to said staple slide, said latch having a pair of ears engageable with said notched portions of said flange to hold said staple slide in said first mentioned recessed area.

2. In a stapling machine, a body portion, the bottom of said body portion being cut away to form a recessed area, a pair of side walls defining opposite longitudinal edges of said recessed area, said side walls each being grooved in a longitudinal direction and having a vertical recess extending at right angles to said longitudinally extending grooves, a staple slide positioned in said body portion, a pair of horizontal flanges extending outwardly from opposite sides of said slide and engageable with said longitudinally extending grooves to permit longitudinal sliding movement of said staple slide relative to said body portion and to prevent relative vertical movement between said staple slide and said body portion, and a releasable latch hinged to said staple slide and engageable with said vertical recesses in said body portion to hold said staple slide against longitudinal movement relative to said body portion.

3. In a stapling machine, a body portion, a pair of elongated side walls and a transverse front wall depending from said body portion to define a recessed area therebetween open at the rear of the body, tracks in each of the side walls opening inwardly towards the recessed area, an elongated staple supporting slide having outwardly extended flanges on opposite sides thereof which flanges slidably fit into the tracks in the side walls, a detent in one of said walls adjacent the rear, and a latch pivotally secured to the rear end of the slide provided with a detent engaging finger whereby to secure the slide within the recessed area in the body on engagement of the detent by the finger, disengagement of the finger and notch freeing the slide for complete withdrawal thereof from said body.
